CLAIM

The ornamental design for a watercraft glide motor system, as shown and described.

DESCRIPTION

FIG. 1 is rear view of a watercraft glide motor system showing my new design;

FIG. 2 is a right side view thereof;

FIG. 3 is a left side view thereof;

FIG. 4 is a front view thereof;

FIG. 5 is a top view thereof;

FIG. 6 is a bottom view thereof;

FIG. 7 is a top rear perspective view thereof; and,

FIG. 8 is a front bottom perspective view thereof.

The broken line showing not-claimed items illustrated in figures, e.g. another motor, propeller, and propeller shield in FIG. 1, FIG. 2, and FIG. 4 through FIG. 8, is included for the purpose of illustrating environmental structure and forms no part of the claimed design.
